(57) **CLAIM**

The ornamental design for a linear actuator, as shown and described.

DESCRIPTION

FIG. 1 is a perspective view of the linear actuator.

FIG. 2 is a front view of the linear actuator shown in FIG. 1.

FIG. 3 is a left side view of the linear actuator shown in FIG. 1.

FIG. 4 is a right side view of the linear actuator shown in FIG. 1.

FIG. 5 is a rear view of the linear actuator shown in FIG. 1.

FIG. 6 is a top view of the linear actuator shown in FIG. 1.

FIG. 7 is a bottom view of the linear actuator shown in FIG. 1; and,

FIG. 8 is lower perspective view of the linear actuator shown in FIG. 1.

1 Claim, 8 Drawing Sheets
